RECOIL AND SHOCK ABSORBING MEANS FOR A RECIPROCATING GUN

Bernard Maillard, Geneva, Switzerland, assignor to Brevets Aero-Mecaniques S.A., Geneva, Switzerland, a society of Switzerland

Application October 3, 1955, Serial No. 538,227

Claims priority, application Luxembourg
October 16, 1954

2 Claims. (Cl. 89—44)

The present invention relates to a gun system including at least one gun movable as a whole for recoil with respect to a support (for instance a gun mount or a part of the framework of an aircraft) against the action of resilient means, that is to say a gun the firing cycle of which is independent of its recoil cycle. The invention is more especially, although not exclusively, concerned with gun systems including an automatic gun at least one part of the operation of the feed device of which is controlled by the recoil of the gun with respect to its support.

The main object of my invention is to provide a system of the above mentioned kind which is better adapted to meet the requirements of practice than those used up to the present time.

The essential feature of my invention consists in interposing, between the gun and the support of such a system, gas operated means for urging the gun in the recoil direction with respect to the support, during the recoil movement of the gun, said last mentioned means being fed with gas through tap means provided in the gun barrel so as to supply powder gases to said means every time a shot is fired by the gun.

A preferred embodiment of my invention will be hereinafter described with reference to the accompanying drawing, given merely by way of example, and in which:

Fig. 1 is a diagrammatic elevational view with parts cut away of a gun system constituted by a small bore automatic gun mounted in an aircraft wing, this system being made according to my invention.

Figs. 2 and 3 are sectional views on an enlarged scale showing details of said gun system.

The gun proper and the means for fixing it to the aircraft wing are devised in any suitable manner such that the firing cycle of the gun is quite independent of its recoil cycle.

This means that the automatic operation of the gun takes place always in the same fashion whatever be the manner in which this gun is mounted on its support and therefore whatever be the speed and the length of recoil, which would not be the case for instance if unlocking of the breech-lock were a consequence of the recoil of the gun barrel and only took place after said gun barrel has recoiled a given distance. As a matter of fact, in such a case, the rate of fire depends upon the speed of recoil. On the other hand, the amplitude of the recoil movement is practically fixed by construction and cannot be modified.

As shown by the drawings, the gun system according to my invention comprises a gun 1 having a movable breech-block 2 slidable in a breech case 3, this breech-block, which is urged forwardly by a recuperator spring 4, being adapted to meet, at the end of its recoil stroke, a spring 5 acting as a shock-absorbing and accelerating element capable, every time a shot has been fired, of quickly returning the breech-block in the forward direction.

Said breech-block 2 is locked, every time a shot is fired,

2

in its front end position, by a device which is released when the shell, after having moved a given distance through the gun barrel, opens a tap hole through which gases can pass so as to operate a lock release device. It is quite obvious that in such a case the firing cycle remains always similar to itself whatever be the recoil cycle (this last mentioned cycle must of course be of a duration at most equal to that of the firing cycle but is generally much shorter).

10 This gun is supported at the front by a wing framework element 6 through a ball and socket device including a ball 7 in which the gun can slide, every time a shot is fired, under the effect of recoil, against the action of a return spring 8. At the rear, the gun is supported by an arm 9 hinged, at its ends, respectively to the gun and to an element of the wing framework.

This arrangement, which is well known in the art, makes it possible on the one hand to adjust the direction of fire of the gun with respect to the aircraft and on the other hand to permit displacements of said gun with respect to the wing under the effect of recoil.

A feed mechanism 10 is provided for feeding cartridges to the gun. This feed mechanism does not participate in the recoil movement but is connected on the one hand, in a sliding fashion, with the gun, and on the other hand, for instance through a link 11, to a fixed point of the wing framework, for instance to element 6 thereof.

As it is well known, the operation of the feed mechanism is obtained as a result of the relative displacements 30 taking place between the gun and this mechanism. For this purpose, for instance, a finger 12 carried by the gun comes, on every recoil stroke of the gun, to lift a roller 13 the displacements of which serve to wind up the spring which operates the feed mechanism.

35 Now, according to my invention, I interpose between gun 1 and the gun supporting part of the aircraft framework a gas operated device, fed with gas tapped from the gun barrel every time a shot is fired, for urging the gun in the recoil direction with respect to part 6.

40 For this purpose, in the construction shown by the drawings, the gun barrel carries a piston 14 movable in a cylinder 15 rigid with ball element 7. A gas tap 16, provided in the wall of the gun barrel, feeds powder gases into said cylinder 15 when the projectile shot by the gun has moved past said gas tap, whereby the whole 45 of the gun is urged rearwardly with respect to the wing framework element 6.

45 It will be understood that the action of the powder gases on piston 14 exerts on return spring 8 an action which is added to that of recoil proper. Thus, other things being equal, this return spring can be made stronger than if it were subjected only to the action of recoil, which may be already be very advantageous when it is desired to have a return spring 8 which is very strong so as to perform as quickly as possible the forward movement returning the gun into battery position. It should be noted that such a quick forward movement of the gun has the advantage of reducing the disturbing influence of the shock exerted by the breech-block, at the end of its rearward stroke, on spring 5. This shock normally tends to slow down the forward return movement of the gun and might even, in some cases, start back into rearward direction the gun that is returning forwardly. It will be understood that the higher the force that produces the forward return movement of the gun, the more reduced is the perturbing action of the shock of the breech-block against spring 5 at the end of the rearward stroke of said breech-block.

70 Thus, the device according to my invention is already very interesting even if the recoil of the gun does not control the operation thereof.

However, when, as already indicated, the recoil move-

ment of the gun serves to operate a feed device, my invention is more particularly interesting because it permits obtaining, for given characteristics of return spring 8, an energy as high as necessary for the operation of said feed mechanism.

In the construction of Fig. 1, the active area of piston 14 will be given a value such that gun 1 is returned rearwardly with respect to fixed part 6, and therefore with respect to feed mechanism 10, with such a force that, account being taken of the reaction of return spring 8 and of the work absorbed by the operation of the feed mechanism, recoil takes place with the necessary amplitude. As for return spring 8, it will advantageously be given resilient characteristics such that, on every shot, the forward return movement of the gun with respect to the wing has already been effected to the desired amount when the breech-block 20 of the gun comes to strike spring 5 which is to return said breech-block in the forward direction. It is known that such a condition is necessary to obtain the highest possible rate of fire for a given gun.

Advantageously, the gun system above described further includes a shock-absorbing system. Such a system may be constituted for instance by a plurality of elementary shock-absorbers interposed between gun 1 and its support, for instance (as shown by Fig. 2) between a ring 17 carried by the gun barrel and a ring element 18 rigid with ball 7. These shock-absorbers may be made of any suitable construction, preferably such that they do not brake the recoil stroke but slow down at least the end of the forward return movement of the gun. For instance, they may be made so that each of them consists of an oil filled cylinder 19 in which moves a piston 20 provided with at least one check valve 21 producing a braking action during the return forward movement of the gun.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A gun system comprising, a fixed support, a gun

movable for recoil and counterrecoil with respect to said support, resilient means between said gun and said support for urging said gun to a fixed battery position with respect to said support, supplementary recoil impulse means including a cylinder mounted in said support and fixed with respect thereto and a piston rigid with the gun barrel and slidable within said cylinder with a gas tap connecting the inside of the gun barrel with the cylinder whereby gases passing into said cylinder act against said piston to impart a supplementary recoil impulse to the gun, cartridge feed mechanism mounted in a fixed position with respect to said support, cooperating means carried by said feed mechanism and said gun for operating the feed mechanism, a breech block slidable with respect to said gun, a spring element mounted on said gun behind said breech block for acting against said breech block for returning the breech block to the forward position thereof, said supplementary recoil impulse means imparting sufficient recoil to operate said cartridge feed mechanism and said resilient means causing said gun to begin counterrecoil movement prior to engagement of said breech block with said spring element to assist in returning the breech block to the forward position thereof.

2. A gun system according to claim 1 and further including shock-absorbing means interposed between said support and said gun to slow down the end of the forward return movement of said gun with respect to said support.
